UNITED STATES PATENT OFFICE.

FRED S. ENGLISH, OF NEW LONDON, CONNECTICUT.

SHEET-DELIVERY MECHANISM FOR PRESSES.

Application filed March 5, 1925. Serial No. 13,345.

The present invention comprises mechanism for taking sheets as they are given up by a movable carrier such as an impression cylinder of a printing press and for delivering the sheets at a given place, such as in the form of a pile on a support or pile table. The device is useful as applied to such machines as printing presses, cutting and creasing presses, etc., and I have chosen here to illustrate my invention as applied to a two-revolution, two-color, printing press which is sufficient to teach the application of my invention for other purposes.

There are two main objects accomplished by the present invention. One is, that the press or other machine may be run faster with the present delivery device without materially increasing the feet-per-minute speed of the delivery members; or, the speed of the delivery may be increased, thus permitting an additional increase in impressions per hour of the press.

Another object accomplished is that all parts of the delivery device may be so removed from the cylinders of the press that complete access may be had to the cylinders or other form or plate carrying members for the purpose of applying make ready thereto or for any other purpose.

In the delivery devices heretofore used employing the printed side up or tape delivery it has been customary to drive the sheet carrying carriage by a crank motion or some similar device, whereby the carriage started from a dead center or stop, then increased to a maximum speed about the middle of the stroke and then gradually decreased in speed to a dead center or zero at the extreme end of the movement. The tapes on the carriage, in such cases, never moved at a speed equal to the cylinder from which the sheets were taken, except, possibly, for a brief period at about the middle of the stroke of the carriage and after the sheet was placed upon the carriage. When the leading edge of the sheet started out on the carriage tapes the latter were moving very slowly, having just started from a dead stop, and as a result of the greater speed of the sheet over the carriage tapes on which it was placed, the sheet tended to buckle, especially if it was composed of light stock, thereby clogging the press and often requiring a temporary stoppage.

There are certain known factors entering

into the operation of this type of delivery which may be here considered. For instance, the shorter the run or trip of the delivery carriage between the point at which it receives the sheet and the point at which it delivers it upon the pile table, the greater the slippage between the sheet and the delivery carriage tapes when the sheet first passes onto them, because the tapes run slower. On the other hand, if the carriage run is lengthened this increases the speed, in feet per minute, at which it must travel in order to cover the increased distance in time with the operations of the press. This requires increased power and increases vibration, among other things, and the sheet travels excessively fast at the middle of the carriage stroke making it more difficult to stop the sheet when the carriage stops.

In the present case I take advantage of a relatively short carriage run and provide means to prevent the sheet from slipping on the tapes as it comes off the cylinder of the press. This overcomes the objections first above mentioned. I accomplish this result by employing auxiliary means operating preferably at or near cylinder speed for primarily taking the sheet and for transferring it onto the carriage tapes at a time when the latter have reached a speed more nearly equal to that of the sheet. In the fullest embodiment of my invention this auxiliary means is adjustable in order to vary the position at which the sheet commences to transfer onto the carriage tapes in order to vary the operation to suit the different requirements. Other advantages will be made apparent in the following detailed description of my invention.

In the drawings forming part of this application,

Figure 1 is a side elevation of a portion of a rotary press having my invention applied thereto,

Figure 2 is a diagrammatic view of the tapes of the delivery carriage,

Figure 3 is a plan view of the delivery device,

Figure 4 is a side elevation corresponding with Figure 1 but with the delivery device and inking mechanism moved forward to permit access to the cylinders,

Figure 5 is an enlarged side elevation of the parts of the delivery mechanism adjacent the cylinder,

Figure 6 is a plan view of the same parts, belts 220 at a time when the latter are traveling at about the same speed as the sheet. For this purpose I have mounted the shafts for driving the carriage,

Figure 8 is a plan view thereof, and Figure 9 is an end view of the front carriage rollers.

In Figure 1 I have shown only one end

15. der 11. The sheet, after traveling around with the cylinder 11, is taken by the delivery mechanism, as will be pointed out herein-after. There is a complete inking unit, 250 for applying ink to the form or plate on the cylinder 12 and this is mounted on a sliding carriage 251 which can be moved toward and from the cylinder 12 by means of the hand wheel 252 mounted on the shaft 253; a pinion 166 on this shaft operating on the 25 stationary rack 165 to move the carriage.

The sheets are taken individually from the cylinder 11 by the delivery mechanism and they are conveyed to and delivered upon, a pile table or support 233 which is carried upon cables and which is automatically lowered step by step as the pile of sheets on the table 233 increases in depth, whereby the top of the pile remains at a given height. The mechanism for lowering the pile table is not shown in detail herein as any of the known devices for this purpose may be used. In Figure 1 I have shown the inking mechanism close up to the cylinder 12 for printing and in Figure 4 I have shown it moved forward to permit access to the cylinders. In Figure 3 I have shown the delivery carriage close to the impression cylinder 11 or at the time a sheet leaves this cylinder, and in Figure 4 I have shown the delivery device moved entirely forward to permit access to the cylinders.

The wheels 169 mounted on the shaft 188 and forming part of the auxiliary sheet handling mechanism, operate at the same surface speed as the cylinder 11. Around these wheels or pulleys engage the endless tapes 207 which also engage around the wheels or pulleys 206 mounted on the cross shaft 205 at some distance away from the wheels 169. The top runs of these belts 207 lie between the tape belts of the reciprocating carriage and at least the first part of the upper runs of the belts 207 (near the cylinder 11) travel in a plane slightly above

60 the plane of the carriage belts 220. The planes of these two sets of belts 207 and 220 cross at some point, such as at 171 in Figure 2, and this point is subject to adjustment so that the leading edge of the sheet may be caused to transfer from the belts 207 to the

ing at about the same speed as the sheet. For this purpose I have mounted the shaft 205 in the end of an arm 202 which is pivoted on a stud 201. Another arm 202' 70 extending from the arm 202 and moving with it, has a block 203 in which there is an adjustable set screw 204 the end of which rests on the bar or rail 177. By adjusting this screw 204 the arms 202 may be rocked to alter the position of the shaft 205 and wheels 206, and thereby control the point 171 at which the planes of the belts 207 and 220 cross each other.

In former practice, the devices for carrying the delivery or stripper fingers 172 for stripping the sheet off the cylinder 11 as well as the cutter wheel shafts and the wheels and gears 168, 169, 191, and 192 were generally fixed close to the cylinder 11 so that these parts were in the way when access to the cylinder was desired. In the present case these parts are all mounted to slide away from the cylinder, so that all parts of the cylinders are accessible. The 80 85 90

part of the cylinders are accessible. The bracket 178 is mounted on a fixed rail 177 (it being understood that the parts are duplicated at opposite sides of the press) which is high enough for the operator to pass under it and to stand between the opposite rails 177 and get at any part of the cylinder 11 between the transfer cylinder, around to the plate cylinder. The brackets 175, bolted firmly to the side frames of the press, lie outside of and extend above the cylinder 11 and they support one end of the rails 177. Disposed some distance from the brackets 175 there are brackets 176 bolted to the side frame of the press and the forward ends of the rails 177 are bolted to these brackets 176. There is a bracket 178 hanging on each rail 177 and they extend down inside the latter and each has a lip 179 extending over the top of a rail 177, so that these brackets are slidably supported upon the rails 177. These brackets 178 are adapt-

the rails 177. These brackets 178 are adapted to be moved along the rails 177 by means of a hand wheel 180 attached to the shaft 181 the latter carrying pinions 182 which mesh with the rack teeth 183 on the under edges of the rails 177. The teeth 183 are arranged the whole length of the rails 177 although only a few teeth are shown in the drawings. When the brackets 178 are moved up into position near the impression cylinder they rest against the stop members 184 and there is a latch 236 which fits into a notch in the collar 238 for the purpose of holding the brackets 178 in this position.

There is a track or slide rod 185 attached to each bracket 178, the other ends of these tracks being mounted as hereinafter described.

are mounted on a shaft 186 which is journaled in bearings in the brackets 178. In order to rock this shaft so that the fingers 172 will be clear of the cylinder and the sheet 5 during the first revolution of the cylinder in each cycle, and be close to the cylinder during the delivery period, I provide an arm 239 on the shaft 186 which is operated by a lever 240. This lever is operated by a cam 10 (not shown) the same as in present practice.

There is a top cutter shaft 187 journaled in the brackets 178 as well as a bottom cutter shaft 188; and on the ends of these shafts are gears 190, 189, respectively. There is a 15 gear 191 on the shaft 193 meshing with and driving the gear 189 and through it the gear 190. There is a gear 192 on the shaft 193, on which the gear 191 is mounted and it meshes with and is operated by the cylinder gear 194^a. The short shaft 193 on which the gears 191 and 192 are mounted is journaled in a bracket 195 which is fixed to the side frame of the press. From the above 20 it will be apparent that the cutter shafts 187, 188 are positively driven. On the shafts 187, 188 are mounted cutter wheels 168, 169 driven at the same peripheral speed as the cylinder, which serve as cutters to slit or 25 cut the sheet lengthwise as it comes off the impression cylinder as in present practice. These wheels also serve to propel the sheet as it leaves the impression cylinder. They are usually provided with removable cutter blades so that they may serve merely for 30 propelling or for both propelling and cutting the sheet and their use is well known in the art.

I have shown a brace rod 198 connected 35 between the brackets 178 for holding them properly spaced laterally. There is a shaft 40 200 journaled in the brackets 178 and on these there are carried a set of tape wheels or pulleys 199 and around these engage the carriage tapes 220. The tapes 220 and their 45 pulleys function like those of the prior art and for this purpose any usual clutch device is applied to the shaft 200 to permit it to revolve freely in one direction, and to hold it from revolving in the opposite direction. 50 I have shown one form of clutch consisting of a ratchet wheel 241 attached to the shaft 200, and a pawl 242 acts on the teeth of this ratchet wheel to resist the turning of the shaft in one direction. The tapes 207, 55 previously referred to, are driven through the motion of the shaft 188 and these tapes preferably travel at the same speed as the surface of the cylinder 11 so that when the sheet leaves the cylinder it will move onto 60 these tapes which are traveling at the same speed and there will therefore be no tendency for the sheet to buckle, nor to slip on these tapes.

At the forward end of the delivery there 65 is a fixed track or slide rod 208 for sup-

porting and guiding the front end of the delivery carriage and it projects some distance beyond the front end of the press. The construction is duplicated at both sides of the press, so there are two such members 70 208. This track 208 is bolted to the delivery bracket 176 by means of screws 209 and it is also bolted to the front legs 245 of the extended portion of the delivery.

There is attached to the forward end of 75 each slide rod or rail 185 a bracket 210 by means of the bolts 211. This bracket carries a tape roll 212 the roll being free to revolve in the bracket. The slide rod 208 is just outside of the slide rod 185 and it 80 therefore operates together with the bracket 210 and the shoulder on the roller 212 to hold the slide rod 185 in position crosswise of the press. There is a small gib 213 bolted on top of the slide rod 185 and it is free to 85 slide along on the slide rod 208 and it serves to hold the front end of the slide rod 185 from dropping downwardly.

The carriage proper consists of a pair of 90 carriage racks 214 having teeth on its lower edge the full length and these racks are supported by wheels 215, 216 journaled thereto on the slide rods. The racks 214 at the back end carry a set of tape tightening wheels 217 supported on spindles and brackets attached to a member 218. This conforms 95 with present practice so that further description of these tighteners is unnecessary.

At the front end of the carriage there is 100 a roller 219 mounted on a shaft connected between the racks 214 and this roller is free to turn on this shaft in the direction of the arrow in Figure 7 and it is prevented from turning in the opposite direction by a pawl 244 which engages a small ratchet wheel 243 105 on the end of the roller 219. The endless tapes 220 extend around the roller 219.

The carriage is reciprocated in time with 110 the operation of the press by means of an intermediate gear 221 which revolves freely on a stud 222; and this gear 221 meshes with and is driven by the gear 223 which is mounted on a shaft 224. The shaft 224 runs freely in the brackets 176 and outside of the bracket there is a gear 225 which meshes 115 with and is driven by the rack 226 the latter being held in position by means of a flanged roller 227. The rack 226 is reciprocated by means of a bell crank lever 228 and the latter is rocked by means of the pitman 229 which is pivoted to the lever 230 and the latter is operated through the pitman 231 the latter being operated from the cross shaft (not shown) of the press.

The tape belts 220 may be operated the 120 same as the corresponding belts are operated on the well known Babcock press and as has been repeatedly described in the patents of George P. Fenner. These endless belts travel around the stationary roller 199 near 125 130

the cylinder 11, thence around the roller 219 which is on the forward end of the carriage, thence around the roller 217 which is on the rear of the carriage; thence around the stationary roller 212 and thence back to the roller 199. The usual clutches will be provided for causing the top runs of the belts 220 to move forwardly when the carriage moves forwardly and for causing this top run to remain idle when the carriage moves rearwardly. These devices are well known in the art so that further description thereof is unnecessary.

15 *Operation.*

As the sheet is ready for delivery after having traveled around with the cylinder 11 it is stripped from the cylinder 11 by the stripper fingers just as the grippers on the cylinder 11 release the leading edge of the sheet; and the sheet then passes between the cutting rollers 168, 169 if these are employed, and the sheet passes on to the tape belts 207 which are at all times traveling at a speed the same or approximately the same as the surface speed of the cylinder 11, so that the sheet is taken by these belts just as fast as it leaves the cylinder 11 and therefore there will be no tendency for the sheet to buckle, regardless of the kind of stock used. When the forward edge of the sheet reaches the point 171 where the planes of the top runs of the belts 207 and the top runs of the belts 220 cross each other the edge of the sheet will commence to move onto the belts 220. At this time the upper runs of the belts 220 will be moving to the left in Figure 2 at about the same speed as the belts 207 so that these belts 220 will take the sheet from the belts 207 without buckling the sheet in any way. The sheet will be carried along on the upper runs of the belts 220 and when the carriage has completed its first forward movement, the sheet will have entirely passed onto the belts 220 and it will lie horizontally on these belts and about midway the delivery (front to back). When the carriage makes its return stroke, the top runs of the belts and the sheet remain stationary so that when the carriage gets to the back end of its stroke as shown in Figure 1 the leading edge of the sheet will lie along the top of the front carriage roller 219. When the carriage starts on its second forward stroke, the top runs of the belts 220 and the sheet move with it so that when the carriage completes its second forward stroke the sheet will lie horizontally on the belts and directly over the pile table 223. When the carriage makes its second return stroke toward the cylinder 11, the tapes 220, operating as in the ordinary Babcock press, will peel off from under the sheet and the latter will fall upon the pile table 223. These operations will be repeated at each complete operation of the press.

By means of the hand crank 180 the entire mechanism may be telescoped into the position shown in Figure 4 leaving only the bracket 175 and the rail 177 at each side of the press and at the end of the cylinder, so that the operator may step in under the rail 177 and stand up straight between these rails and he will have access to both cylinders 11, and 12 which latter will be entirely uncovered. It may be noted that the shaft 193 does not extend across the press so that at this time it will not be in the way of the operator. At the time this telescoping operation takes place the carriage should be at the extreme front end of its stroke or directly over the pile table; or else the pitman 226 should be disconnected from the lever 228 by detaching them at the pin 234, so that regardless of the position of the parts of the press the carriage may readily move forward. In order to facilitate replacing the connection between the pitman 226 and the lever 228 I have provided a hand wheel 235 which revolves the shaft 224 for the purpose of moving the parts back to their original position. It will be apparent that the entire delivery mechanism may thus be telescoped instead of telescoping only a part of it.

It may be found desirable to adjust the point 171 at which the planes of the upper runs of the belts 207 and 220 cross each other according to the character of the work and the nature of the stock which is being handled. This may readily be accomplished by turning the set screw 204 to either raise or lower the arm 202 which carries the shaft 205, on which the tape rollers 206 are mounted. As the lever 202 is elevated to a higher position the point 171 will be moved to the left in Figure 2 so that the sheets will begin to move onto the tapes 220 when the latter have reached a relatively higher speed; whereas, if the arm 202 is lowered, the point 171 will be shifted to the right in Figure 2 and the sheets will commence to move onto the belts 220 at a time when the latter are moving at a relatively slower speed. From this it will be apparent that the point 171 may be varied to suit any condition of operation.

Having described my invention what I claim is:

1. The combination of a press having a movable impression member for holding the sheet as it is printed, and means for delivering the sheets from said impression member, comprising a reciprocating carriage for carrying the sheets, and belts arranged to receive the sheets from said impression member and adapted to transfer them to said carriage for delivery by the latter, said belts being adjustable to alter the position at which the sheet transfers from said belts to said carriage.

2. The combination of a press having a movable impression member for holding the sheet as it is printed, and means for delivering the sheets from said impression member, comprising a reciprocating carriage for carrying the sheets, and belts traveling approximately at the same speed as said impression member, arranged to receive the sheets therefrom, and adapted to 10 transfer the sheets to said carriage while the latter is in motion for delivery by said carriage, said belts being adjustable to alter the position at which the sheet transfers from said belts to said carriage.

15 3. The combination of a press having a movable impression member for holding the sheet as it is printed, and means for delivering the sheets from said impression member, comprising a reciprocating carriage for 20 carrying the sheets, and belts having fixed locations horizontally and traveling approximately at the same speed as said impression member, arranged to receive the sheets therefrom and adapted to transfer 25 the sheets to said carriage while the latter is in motion, for delivery by said carriage, said belts being adjustable vertically to alter the position at which the sheet transfers from said belts to said carriage.

30 4. The combination of a press having a movable impression member for holding the sheet as it is printed, and means for delivering the sheets from said impression member, comprising a reciprocating carriage for 35 carrying the sheets, and means for operating said carriage whereby its speed is increased as it moves away from said impression member, and belts traveling at approximately the same speed as said impression member, arranged to receive the sheets therefrom and adapted to transfer the sheets to said carriage while the latter is in motion, for delivery by said carriage, said belts being adjustable to alter the position at which the 40 sheet transfers from said belts to said carriage.

45 5. The combination of a press having a movable impression member for holding the sheet as it is printed, and means for delivering the sheets from said impression member, comprising a reciprocating carriage having belts for carrying the sheets, means for operating said carriage whereby its speed is increased as it moves away from said impression member, and belts disposed intermediate said carriage belts, and traveling approximately the same speed as said impression member, arranged to receive the sheets therefrom and adapted to transfer the sheets to said carriage belts while the latter are in motion, and adjustable means for changing the relative inclination of said belts to alter the position at which the sheet transfers from one set of belts to the other.

60 6. The combination of a press having a

movable impression member for holding the sheet as it is printed, and means for delivering the sheets from said impression member, comprising a reciprocating carriage having belts for carrying the sheets, means for 70 operating said carriage whereby its speed is increased as it moves away from said impression member, and belts traveling at substantially the same speed as said impression member, and receiving the sheets therefrom 75 and adapted to transfer the sheets to said carriage while the latter is moving away from said impression member, and adjustable means for changing the relative inclination of said belts to alter the position at 80 which the sheet transfers from one set of belts to the other.

7. The combination of a press having a movable impression member for holding the sheet as it is printed, and means for delivering the sheets from said impression member, comprising a reciprocating carriage having belts for carrying the sheets, other belts arranged to receive the sheets from said impression member and to deliver them 90 upon the belts, said first belts and said second belts having runs arranged in intersecting planes, and adjustable means for changing the relative inclination of said belts to 95 alter the position at which the sheet transfers from one set of belts to the other.

8. The combination of a press having a movable impression member for holding the sheet as it is printed, and means for delivering the sheets from said impression member, comprising a reciprocating carriage having belts for carrying the sheets, other belts traveling at substantially the same speed as said impression member, for receiving the sheet from the latter, said lat- 100 ter belts being disposed between said carriage belts, said first belts and said second belts having their adjacent runs arranged in intersecting planes, and adjustable means for changing the relative inclination of said belts to alter the position at which the sheet 105 transfers from one set of belts to the other.

9. The combination of a press having a movable impression member for holding the sheet as it is printed, and means for delivering the sheets from said impression member, comprising a reciprocating carriage having belts for carrying the sheets, other belts for receiving the sheets from the impression member, and for delivering them 115 upon the carriage belts, said first and said second belts having runs arranged in intersecting planes, and adjusting means for changing the relative inclination of said runs to alter the position at which the sheet 120 transfers from one set of belts to the other.

10. The combination of a press having a movable impression member for holding the sheet as it is printed, and means for delivering the sheets from said impression 130

member, comprising a reciprocating carriage having belts for carrying the sheets, other belts for receiving the sheets from the impression member and for delivering them upon the carriage belts, said first and said second belts having runs arranged in intersecting planes, and means for adjusting the plane of said second belts to alter the point at which said latter belts transfer the sheets to the carriage belts.

11. In a press the combination of an impression cylinder, rollers between which the sheet passes as it leaves said cylinder, a reciprocating carriage for delivering the sheets, a track on which the carriage is adapted to be moved away from said cylinder, a second track and means movable thereon away from said cylinder, said rollers being carried on said movable means.

12. In a press the combination of an impression cylinder, a reciprocating carriage

for delivering the sheets, belts arranged to receive the sheets from said cylinder and adapted to convey them to and deliver them upon said carriage, a track and means movable thereon toward and from said cylinder and carrying said belts.

13. In a press the combination of an impression cylinder, rollers and stripper fingers co-acting with the sheet as it leaves said cylinder, a reciprocating carriage for delivering the sheets, belts arranged to receive the sheets from said cylinder and to carry them to and deliver them upon said carriage, a track and means movable thereon toward and from said cylinder and carrying said belts, said rollers and said stripper fingers.

Signed at the city and county of New London and State of Connecticut, this 5th day of December, 1923.

FRED S. ENGLISH.
